UNITED STATES PATENT OFFICE.

RAYMOND HUFFORD, OF NEW YORK, N. Y., ASSIGNOR TO K. P. PRODUCTS COMPANY, INC., OF NEW YORK, N. Y., A CORPORATION OF NEW YORK.

GOVERNOR FOR INTERNAL-COMBUSTION MOTORS.

Application filed April 11, 1924. Serial No. 705,732.

To all whom it may concern:

Be it known that I, RAYMOND HUFFORD, a citizen of the United States, and a resident of New York city, in the county, city, 5 and State of New York, have invented certain new and useful Improvements in Governors for Internal-Combustion Motors, of which the following is a specification.

My invention relates to improvements in 10 governors for internal combustion motors and has for its object to provide a governor for this purpose which will be more efficient, accurate and certain in its action than those heretofore in use.

With this and other objects in view, which 15 will be more particularly set forth in the specification, my invention consists of the novel details of construction and combinations hereinafter disclosed and particularly 20 pointed out in the claims.

Referring to the accompanying drawing, Figure 1 is a sectional elevation on the line 1—1 of Figure 2. Figure 2 is a sectional view on the line 2—2 of Figure 1. Figure 25 3 is a sectional view partly broken away on the line 3—3 of Figure 2. Figure 4 is a 30 sectional view on the line 4—4 of Figure 1. Figure 5 is an enlarged sectional view of a modification of the check valve which when 35 in a closed position cuts off communication with the passage communicating between the interior of the governor shell and the cylinder in which is mounted the piston by 40 which the closing movement of the speed regulating valve is continued toward or to 45 closed position. Similar numerals designate similar parts on the several views.

My governor is provided with a shell or 40 body 1, having a cylindrical bore or passage 2, and is provided with an inwardly projecting flange 3 at the outlet end thereof. Mounted in the upper end of the shell is a spacing sleeve 4 having a contracted throat 5. Mounted in the cylindrical bore immediately 45 below the spacing sleeve 4 is a collar 6 having a spider 7. The spider 7 is provided with a centrally positioned cylindrical cup 8, a guide 9 and a cylinder 10. A passage 11 communicates between the cup 8 and the cylinder 10. A bushing 12 is mounted as shown in the spider and in the bushing 12 is mounted a needle valve 13 by which the passage 11 may be more or less closed. A passage 14 communicates between the cylinder 10 and the interior of the 50 governor below the contracted throat 5. A ball valve 15 is mounted in a valve chamber 15a. When the ball is seated, communication between the passage 14 and the interior of the governor is cut off. In Figure 5 I 55 have shown a modification of this valve in which a spring 16 serves to normally hold the ball 17 in closed position on its seat 18. The tension of this spring may be adjusted by means of the screw threaded plug 19. 60 Ports 20 and 21 communicate with the chamber 22 in which the ball valve is mounted. Also formed in the spider 7 is a passage 23 communicating at its lower end with the cylinder 10 at the lower end thereof. The 65 upper end of this passage 23 communicates with a passage 24 and with a passage 25 in the threaded plug 26. The outer end of passage 25 opens into the chamber 27 which has a cover 28 which is loosely fitted over 70 the chamber so as to permit air to flow into said chamber. Mounted in the cylindrical cup 8 is a cylindrical cup shaped valve 29 having ports 30 in the bottom wall thereof and a central threaded recess 31 in which 75 is secured the threaded stem 32 on the guide stem 33, and the parts are locked in position by the lock nut 34 and the cotter pin 35. Formed integral with the guide stem is a 80 piston 36 adapted to reciprocate in the cylinder 10. The lower end of the cylinder 10 and the passage 23 are closed by a plug 37 and a washer 38. Formed in opposite sides of the cylinder 10 are slots 39, and a hole 40 is tapped through the piston 36. A sleeve 85 41, carrying an impact head 42 is mounted concentrically around the cylinder 10 and this sleeve is secured to the piston by means of a pin 43 which passes through 90 oppositely opposed holes 44 located near the top of the sleeve 41. Mounted concentrically around the sleeve 41 is a sleeve 45 having an outwardly extending flange at 46 at the lower end thereof. Formed in this sleeve 47 are oppositely opposed holes 48 which are 95 formed in a plane below the plane of the holes 44. The sleeve 45 thereby serves to hold the pin 43 in position and permits the pin to be removed or placed in position by causing the holes 44 to register with the holes 48. The spider is threaded at 49 to receive an adjusting nut 50 which may be 100 adjusted by the shaft 51 carrying the spiral thread 52. Mounted concentrically around the cylinder is a spiral spring 53, one end 105 110

2
of which bears against the nut 50 and the other end against the flange 46 on the sleeve 45. 54 are perforated ears by which the governor may be secured between a carbureter 57 and the manifold of an engine by bolts passing through said ears. The spider 7 is held in position by a spacing sleeve 55 which has a contracted throat 56. The outlet end of the carbureter 57 is provided with 10 the usual main throttle valve 58.

The operation of my governor is as follows:

When the motor to which the governor is attached is running slowly, the passage 15 of the mixture from the carbureter through my governor to the motor will be comparatively slow and the impact of the mixture on the head 42 will not be sufficient to lift the head and the parts to which it is secured because of the resistance of gravity and of the spring 53. The weight of the head 42 and the parts to which it is secured, and the resistance of the spring, as adjusted by the nut 50, and of gravity are such that 20 when the flow of the mixture and its velocity is increased by the increase in engine speed to approximately the speed for which the governor has been adjusted the head will be lifted, carrying with it the piston 36 and 25 the cup shaped valve 29 and move the valve 29 toward the restricted throat 5 thereby reducing the area of said port. As the valve 29 approaches the closed position it not only reduces the flow of mixture to the motor but 30 causes the pressure above the valve to fall below atmospheric pressure which is communicated to the bottom of the cylinder below the piston by the passages 23, 24 and 25. As the valve 22 is raised this difference in 35 pressure is rapidly increased and as the motor speed is increased the difference in pressure will cause the piston 36 to rise and lift the valve 29 until the throat 5 is nearly closed and further acceleration of the motor 40 prevented. The air leak past the piston 36 is such, and the capacity of the passage 11 as regulated by the needle valve 13 is so limited that the piston 36 will not rise and move the valve 29 toward the closed position 45 until the motor speed approximates the maximum speed for which the governor has been adjusted. The adjusting means are the nut 50, which regulates the resistance of 50 the spring 53 and the needle valve 13 which 55 regulates the capacity of the passage 11. To prevent stealing or racing the motor under a partial load when the throttle valve of the carbureter is nearly closed, I have provided the passage 14 and the ball valve 60 15, which is mounted below the restricted throat 5 and therefore is normally in the closed position, and when the valve 29 is in or approaching the closed position, is normally subjected to a lesser vacuum than the 65 vacuum between the valve 29 and the motor.

When, however, the throttle valve 58 of the carbureter, is nearly closed and the motor is running at approximately the speed for which the governor has been adjusted, a high vacuum is produced within the body of 70 the governor which because of the restriction of the passage 11 by the needle valve 13 as adjusted and of the leak past the piston 36 becomes under these conditions much higher than the vacuum in the upper end 75 of the cylinder 10 causing the ball 17 to rise and open communication between the body of the governor and the upper part of the cylinder 10 through the passage 14, and the passage 14 being of far greater capacity 80 than the passage 11 as it is restricted by the needle valve 13, the leak past the piston becomes negligible and the piston is immediately elevated and the valve 29 moved toward or to closed position, restricting further acceleration of the motor speed. The vacuum or difference in pressure which will normally cause the piston 36 to be actuated can be readily regulated by means of the needle valve 13. This needle valve 13 85 should be so regulated as against the resistance of the spring 53 that, when the impact of the entering mixture on the head 42 has substantially elevated the head and caused the valve 29 to move a substantial 90 distance towards the closed position the vacuum existing between said valve and the motor will cause the piston 36 to so actuate the valve 29 that it will so restrict the flow of mixture as to prevent any further 95 increase in motor speed. The weight of the ball 17, or if the modified form shown in Figure 5 is used, the weight of the ball 17 and the resistance of the spring 16 as adjusted should be such that the negative pressure required to lift the ball 17 will be below 100 the maximum negative pressure which can be created in the passage 2 when the motor is running free or under a small load at a speed for which the governor is adjusted 105 and the throttle valve of the carbureter is manipulated toward the closed position. It will be noted that the piston 36 is in axial alignment with the valve 29 and therefore 110 there will be little or no tendency to throw the moving parts out of alignment and cause undue friction which would prevent the accurate operation of the governor.

Claims:

1. A governor for internal combustion 120 motors comprising in combination a body, a passage in said body through which the combustible mixture may pass to a motor, a valve adapted to reduce the effective area of such passage as it is moved toward its closed position, primary, secondary and tertiary automatic means adapted to cause a movement of such valve toward its closed position.

2. A governor for internal combustion 125

- motors comprising in combination a body, a passage in said body through which combustible mixture may pass to a motor, a valve adapted to reduce the effective area of such passage as it is moved toward the closed position, and primary automatic means adapted to move said valve toward its closed position, secondary automatic means actuated by the negative pressure beyond said valve adapted to move said valve toward its closed position, and means actuated by the negative pressure in said passage anterior to said valve, adapted to cause a movement of said valve toward its closed position.
3. A governor for internal combustion motors comprising in combination a body, a passage in said body through which combustible mixture may pass to a motor, a discharge outlet, a valve adapted to reduce the effective area of such outlet, a cylinder in axial alignment with such valve, a passageway leading from such cylinder to the outside atmosphere and a restricted passageway leading from such cylinder to said passage in said body beyond said valve, a passageway leading from said cylinder to said passage in said body anterior to said valve, an outwardly opening check valve normally closing such passageway, and a piston mounted in said cylinder adapted to operate said valve.
4. A governor for internal combustion motors comprising in combination a body, a passage in said body through which combustible mixture may pass to a motor, a valve adapted to reduce the effective area of said passage when it is moved toward its closed position, a cylinder, a passageway communicating between such cylinder and the outside atmosphere, a restricted passageway communicating between such cylinder and such passage in said body beyond such valve, means for regulating the restriction of such passageway, a second passageway communicating between such cylinder and such passage in such body anterior to said valve, a check valve adapted to normally close said second passageway and a piston mounted in said cylinder adapted to operate said valve.
5. A governor for internal combustion motors comprising in combination a body, a passage in said body through which combustible mixture may pass to a motor, a valve adapted to reduce the effective area of said passage when it is moved toward its closed position, primary means actuated by impact of the mixture flowing through such passage adapted to initiate the closing move-
- ment of said valve, secondary automatic means actuated by the reduction of pressure beyond said valve adapted to continue and complete the closing movement of said valve, and tertiary automatic means actuated by a predetermined reduction of pressure in said passage in said body anterior to said valve adapted to supplement the activity of said secondary means.
6. A governor for internal combustion motors comprising in combination a body, a passage in said body through which combustible mixture may pass to a motor, a valve adapted to reduce the effective area of said passage when it is moved towards its closed position, a cylinder, a passageway communicating between such cylinder and the outside atmosphere, a restricted passageway communicating between such cylinder and such passage in said body beyond such valve, means for regulating the restriction of such passageway, a second passageway communicating between such cylinder and such passage in such body anterior to said valve, a check valve adapted to normally close said second passageway, means for varying the negative pressure required to open such check valve, and a piston mounted in said cylinder adapted to operate said valve.
7. A governor for internal combustion motors comprising in combination a body, a passage through said body through which combustible mixture may pass to a motor, a valve adapted to reduce the effective area of such passage as it is moved toward the closed position, automatic means actuated by negative pressure beyond said valve adapted to move said valve toward its closed position, and secondary automatic means actuated by negative pressure in such passage anterior to said valve adapted to move said valve toward its closed position.
8. A governor for internal combustion motors comprising in combination a body, a passage through said body through which combustible mixture may pass to a motor, a valve adapted to reduce the effective area of such passage as it is moved toward the closed position, automatic means actuated by negative pressure beyond said valve adapted to move said valve toward its closed position, means for regulating the negative pressure required to actuate such automatic means, and secondary automatic means actuated by negative pressure in such passage anterior to said valve adapted to move said valve toward its closed position.

RAYMOND HUFFORD.
